William C. Panzer, Chicago, Ill.

Application May 14, 1945, Serial No. 119,546

Term of patent 14 years

(Cl. D85—2)

To all whom it may concern:

Be it known that I, William C. Panzer, a citizen of the United States, residing in Chicago, Cook County, Illinois, have invented a new, original, and ornamental Design for an Ash Tray or Similar Article, of which the following is a specification, reference being had to the accompanying drawing, forming a part hereof.

3—3 of Figure 1.

I claim:

The ornamental design for an ash tray or similar article, substantially as shown.

WILLIAM C. PANZER.
